UNITED STATES PATENT OFFICE.

WILLIAM E. SHERWOOD, OF CANASTOTA, NEW YORK.

DUMP-WAGON.

1,123,026.

Specification of Letters Patent. Patented Dec. 29, 1914.

Application filed January 13, 1913. Serial No. 741,737.

To all whom it may concern:

Be it known that I, WILLIAM E. SHERWOOD, a citizen of the United States, and a resident of Canastota, in the county of 5 Madison and State of New York, have invented a certain new and useful Dump-Wagon, of which the following is a specification.

This invention relates to dumping wagons 10 and particularly to means for opening and closing the dumping sections or doors, which means is particularly simple in construction, highly efficient and durable in use; and the invention consists in the combinations and 15 constructions hereinafter set forth and claimed.

In describing this invention reference is had to the accompanying drawings in which like characters designate corresponding 20 parts in all the views.

Figure 1 is a longitudinal sectional view, partly broken away, and parts being removed, of a dumping wagon embodying my invention. Fig. 2 is a transverse sectional 25 view on line "A—A", Fig. 1, parts being removed. Figs. 3 and 4, are sectional views looking in opposite directions on a plane extending between the ratchet wheels of the drums. Fig. 5 is a detail view in plan of 30 the holding pawls and contiguous parts. Fig. 6 is a fragmentary view illustrating in plan, the ratchet wheels, and the pawl carried by the end board of the box for holding either ratchet wheel whereby the doors can 35 be dumped singly.

1 is the box of a dump wagon having a pair of dumping doors 2 hinged at their outer edges to the box. The doors 2 are controlled in their opening and closing movements by winding mechanism and means for holding the winding mechanism from retrograde movement. The winding mechanism is in this embodiment of my invention held from unwinding by means operable to release both doors simultaneously, and also by additional means operable to release the doors singly.

In the illustrated embodiment of my invention, the means for controlling the opening and closing of the doors 2 comprises a pair of drums 3, 4 and cables 5 winding on the drums respectively, and means for winding the drums. The cables 5 are connected at 6 and 7 to the drums and run under the 55 free edges of the hinged doors 2 and are

connected to the rear end board 10 of the box in any suitable manner. The cables are here shown as engaging hooks as the hook 11 on the rear end board, but may be connected to an equalizer on the end board or otherwise supported at their rear ends. The drums 3, 4 are arranged in axial alinement and are here shown as a shaft and a sleeve on the shaft.

The means for winding the drums 3, 4 includes ratchet wheels 12, 13 mounted respectively on the drums 3, 4 contiguous to each other and operating means coacting with the ratchet wheels to wind the same. The operating means consists of a lever arranged 65 contiguous to the ratchet wheels 12, 13 and carrying a pawl of sufficient width to engage both ratchet wheels 12, 13 in order to wind both simultaneously, the pawl being shiftable out of engagement with either 70 ratchet wheel 12, or 13 into sole engagement with the other whereby one door can be closed independently of the other or can be started toward its closed position ahead of the other, and, after it has been so started, 75 both doors can then be closed together as when one door is formed with a batten strip that laps the other door.

In the illustrated form of my invention, the operating lever 14 extends between the 85 ratchet wheels 12 and 13, and oscillates about the axis of the drums 3, 4, and the pawl 15, which is wide enough to engage both ratchet wheels 12, 13, is carried at the lower end of a hand lever 16 pivoted between its ends at 90 17 to the operating lever, on a pivot extending in the direction of the oscillating movement of the lever 14. For permitting ratcheting of the pawl 15, the operating lever 14 is formed with an elongated bearing 95 18 extending around the drum 4, this bearing being here shown as mounted on the hub 19 of the ratchet wheel 13. The hand lever 14 is guided in its shifting movement by any suitable means, as a strap 20 embracing the 100 pawl 15 and arranged to limit the lateral shifting of the pawl 15 in either direction. If desired, suitable spring-pressed locking detents or plungers may be used to snap into engagement with the pawl 15 or lever 16, 105 when the pawl is in either of its three operative positions, and this locking means may be carried by the strap 20. During the oscillating movement of the lever 14 backwardly, obviously owing to the elongated 110

bearing 18, the levers 14 and 16 will move endwisely as the pawl 15 ratchets. Upon the forward movement of the levers 14 and 16, the ratchet wheels 12, 13 will be actuated if the pawl 15 is engaged with both ratchet wheels 12, 13 or one of said wheels will be actuated if the pawl is engaged with one ratchet wheel. When the chains 5 are wound up, the levers 14 and 16 are held so that the pawl 15 is out of engagement with the ratchet wheels 12, 13 by means of a shoulder or detent 21 fixed on the lever 16 and coacting with the stationary shoulder 22 provided on one side of the neck 23 of the body of the wagon.

The drums 3, 4 are held from retrograde movement during the winding thereof and after being wound up by pawls 24, 25 coacting with the ratchet wheels 12, 13 and pivoted at 26 to the short arm of a lever 27 which is pivoted at 28 between its ends to the neck 23 of the wagon body, the long arm of the lever 27 being engaged by a catch or trip lever 29 pivoted at 30 and having a pedal 31 by means of which it is operated forwardly to release the lever 27. The catch 29 is also formed with an arm 32 for engaging the long arm of the lever 27 by which the trip lever 29 is reset when the operator depresses the long arm of the lever 27 by engaging his foot with a pedal 27^a on said lever. The long arm of the lever 27 is of sufficient length to have enough resiliency to permit the pawls 24 and 25 to ratchet, as the pawls are formed with shoulders which normally engage stops 27^b on the lever 27 and hold the pawls from downward pivotal movement. Both of these pawls are provided with weights 33 which tend to hold the pawls with their points in engagement with the ratchet wheels. The lever 29 is tripped by pushing the pedal 31 forwardly to permit the long arm of the lever 27 to move upwardly and the short arm thereof forwardly and downwardly carrying the pivots of the pawls 24 and 25 below the dead center lines so that retrograde movement of the ratchet wheels causes the points of the pawls to be carried upwardly. The weights 33 return the pawls to their normal position relatively to the lever 27.

The additional holding means for holding either door from moving downwardly while permitting of the movement of the companion door, or for permitting both doors to move downwardly substantially simultaneously, includes a pawl 34 preferably mounted on the wagon body. As here shown, said pawl 24 co-operates with the ratchet wheels 12, 13 and holds one drum from unwinding movement, and is supported by the front end board 35 of the box and shiftable to engage either ratchet wheel 12 or 13, or into position to be out of engagement with both ratchet wheels. As here shown, the

pawl 34 is slidable laterally on a shaft 36 carried on the front side of the front end board 35, in lugs 37.

In operation, if it is desired, to hold the door operated by the chain 5, which is connected to the drum 4, the pawl 34 is moved into engagement with the ratchet wheel 13 so that upon the operation of the trip lever 31 the drum 4 will be held from unwinding movement. If it is desired to hold the door 2 connected to the chain 5 which winds on the drum 3, the pawl 34 is shifted into engagement with the ratchet wheel 12 and if it is desired to dump both doors in the ordinary manner, the pawl 34 is shifted to one side of both ratchet wheels 12 and 13. When the doors are dumped singly, the box may be provided with a lengthwise partition 38.

What I claim is:

1. In a dumping wagon, a box having movable dumping doors, and means for closing said doors including winding drums capable of complete rotation independently of each other having ratchet wheels arranged side by side, an oscillating operating lever, and a pawl carried by said lever and having a tooth of sufficient width to engage both wheels, the pawl being shiftable into engagement with both wheels and out of engagement with one wheel into sole engagement with the other, substantially as and for the purpose described. 85

2. In a dumping wagon, a box having dumping doors, and means for closing the doors comprising a pair of drums capable of complete rotation independently of each other, cables winding on the drums and connecting the drums and the doors respectively, ratchet wheels mounted on the drums respectively, an oscillating operating lever arranged contiguous to the ratchet wheels, and a hand lever pivoted between its ends to the operating lever by a pivot extending transversely of the operating lever in the direction of movement of the operating lever, the hand lever having a pawl of sufficient width to engage both ratchet wheels, and being shiftable on its pivot for moving the pawl into engagement with both ratchet wheels and out of engagement with one ratchet wheel and into sole engagement with the other, substantially as and for the purpose specified. 95

3. In a dumping wagon, a box having dumping doors, and means for closing the doors comprising a pair of drums arranged in axial alinement and capable of complete rotation independently of each other, cables winding on the drums and coacting with the doors respectively, ratchet wheels mounted respectively on the drums side by side, an operating lever extending between the ratchet wheels and movable about the axis of the drums, and a pawl carried by the operating lever and being of sufficient width 100

to engage both ratchet wheels and being shiftable into engagement with both ratchet wheels, and out of engagement with one ratchet wheel into sole engagement with the other, substantially as and for the purpose set forth.

4. In a dumping wagon, a box having dumping doors, and means for closing the doors comprising a pair of drums arranged in axial alinement and capable of complete rotation independently of each other, cables winding on the drums and coacting with the doors respectively, ratchet wheels mounted respectively on the drums side by side, an operating lever extending between the ratchet wheels and movable about the axis of the drums, and a hand lever pivoted between its ends to the operating lever by a pivot extending transversely of the operating lever in the direction of movement of the operating lever, the hand lever having a pawl arranged to coact with the ratchet wheels, the pawl being of sufficient width to engage both ratchet wheels and the lever being shiftable on its pivot for carrying the pawl into engagement with both ratchet wheels or for carrying the pawl out of engagement with one ratchet wheel and into sole engagement with the other, substantially as and for the purpose described.

5. In a dumping wagon, a box having two dumping doors, and means for controlling the opening and closing of the doors comprising two independently rotatable drums, cables winding on the drums and coacting with the doors, a ratchet wheel carried by each drum, winding means coacting with the ratchet wheels and capable of oscillation about the axis of the drums and of oscillation on a different axis, and having an engaging part of sufficient width for engaging both ratchet wheels for shifting the same in unison, means independent of the winding means for normally holding the ratchet wheels from retrograde movement and oper-

able to release both ratchet wheels simultaneously to permit both doors to be dumped, and additional means independent of said winding means for coöperating with the ratchet wheels and operable for holding either ratchet wheel independent of the other, substantially as and for the purpose described.

6. In a dumping wagon, a box having two dumping doors, and means for controlling the opening and closing of the doors comprising two independently rotatable drums, cables winding on the drums and coacting with the doors, a ratchet wheel carried by each drum, a hand lever coacting with the ratchet wheels and capable of oscillation about the axis of the drums, and of oscillation on a different axis, and having an engaging part of sufficient width for engaging both ratchet wheels for shifting the same in unison, means independent of the lever for normally holding the ratchet wheels from retrograde movement, and operable to release both ratchet wheels simultaneously to permit both doors to be dumped, and additional means independent of said hand lever for coöperating with the ratchet wheels and operable for holding either ratchet wheel independent of the other, said additional means being carried by the front end-board of the wagon body, and comprising a shaft extending in a direction parallel to the axis of the ratchet wheels, and a single detent carried by the shaft and slidable thereon lengthwise of the same, substantially as and for the purpose set forth.

In testimony whereof, I have hereunto signed my name in the presence of two attesting witnesses, at Syracuse, in the county of Onondaga, in the State of New York, this 11th day of January, 1913.
